UNITED STATES PATENT OFFICE.

LUCIE ARVILLA GRAHAM, OF NEW YORK, N. Y.

DESIGN FOR A SKIRT AND WAIST SUPPORTER.

SPECIFICATION forming part of Design No. 31,383, dated August 8, 1899.

Application filed July 13, 1899. Serial No. 723,736. Term of patent 7 years.

To all whom it may concern:

Be it known that I, LUCIE ARVILLA GRAHAM, a citizen of the United States, residing at New York, in the county of New York, State of New York, have invented a certain new and original Design for Skirt-Supporters, of which the following is a description, reference being had to the accompanying drawings and to the letters of reference marked thereon.

10 My invention relates to a new and original design for skirt and waist supporters; and the leading feature consists in a skirt and waist supporter of the shape and configuration hereinafter described, and illustrated in 15 the accompanying drawings, in which—

Figure 1 is a front elevation, and Fig. 2 a side elevation, of a skirt and waist supporter embodying my design.

In the drawings, A represents a bar or plate 20 provided with the longitudinal tapering open-

ings a, the central solid body portion b, the round openings c at the ends, and the downwardly-extending arms d. Projecting upwardly from about the central point of the bar A is a lug or ear e, which is enlarged at 25 its upper end and connected with the body of the bar by the curved portions f.

The leading feature of my design consists in the bar or plate A, having the upwardly-projecting lug or plate e with the widened 30 upper portion.

I claim—

The design for a skirt and waist supporter, substantially as shown and described.

In testimony whereof I affix my signature 35 in presence of two witnesses.

LUCIE ARVILLA GRAHAM.

Witnesses:

FRANK A. VOSBURGH,
D. B. GRAHAM.
